(57) **CLAIM**

The ornamental design for a gripper jaw, as shown and described.

DESCRIPTION

FIG. 1 is a front elevation view of a gripper jaw showing my new design;

FIG. 2 is a rear elevation view thereof;

FIG. 3 is a top view thereof;

FIG. 4 is a bottom view thereof;

FIG. 5 is a right side elevation view thereof;

FIG. 6 is a left side elevation view thereof;

FIG. 7 is a front, bottom, left side perspective view thereof;

FIG. 8 is a rear, top, right side perspective view thereof; and, FIG. 9 is a rear, left side perspective view and a front, right side perspective view showing the gripper jaw in its environment of a robotic device.

The broken line portion of the figure drawing is included to show environment and represents unclaimed subject matter only and forms no part of the claimed design.
